The ornamental design for the shield for electromagnetic radiation for personal computer, as shown and described.

DESCRIPTION

FIG. 1 is a right, top, front perspective view of the shield for electromagnetic radiation for personal computer showing our new design;

FIG. 2 is a front elevational view thereof;

FIG. 3 is a left, top, rear perspective view thereof;

FIG. 4 is a right side elevational view thereof;

FIG. 5 is a rear elevational view thereof; and,

FIG. 6 is a top plan view thereof.

The bottom of the article is substantially plain and unornamented.

FIG. 1

FIG. 2

FIG. 3

FIG. 5

FIG. 4

FIG. 6
